CLAIM

I claim the ornamental design for the rack hitch mount, as shown and described.

DESCRIPTION

FIG. 1 is a perspective view of the rack hitch mount showing my new design;

FIG. 2 is a top plan view thereof;

FIG. 3 is a front elevational view thereof;

FIG. 4 is a right side elevational view thereof;

FIG. 5 is a back elevational view thereof;

FIG. 6 is a left side elevational view thereof; and,

FIG. 7 is a bottom plan view thereof.
